FIG. 1

FIG. 2

FIG. 1 is a top plan view of a mat showing my new design;

FIG. 2 is a top plan view of two disengaged mat elements of the mat of FIG. 1; and

FIG. 3 is a bottom plan view of the two disengaged mat elements of FIG. 2.

The characteristic feature of the design resides in the grid-like pattern on the bottom face in combination with the rectangular elements thereon, as shown.

I claim:

The ornamental design for a mat or similar article, as shown and described.
